Primary Examiner — Amy C Wierenga*Assistant Examiner* — Andrea Marie McKay*(74) Attorney, Agent, or Firm* — Avyno Law P.C.(57) **CLAIM**

We claim the ornamental design for a heater, as shown and described.

DESCRIPTION

FIG. 1 is a top, front perspective view of a heater of the present invention.

FIG. 2 is a bottom, rear perspective view of a heater of the present invention.

FIG. 3 is a side elevation view of the left side of the heater of FIG. 1.

FIG. 4 is a side elevation view of the right side of the heater of FIG. 1.

FIG. 5 is a front elevation view of the heater of FIG. 1.

FIG. 6 is a rear elevation view of the heater of FIG. 1.

FIG. 7 is a top plan view of the heater of FIG. 1; and,

FIG. 8 is a bottom plan view of the heater of FIG. 1.

In the drawings, the broken lines depict portions of the heater that form no part of the claimed design, and the dash dot broken line is a boundary line that form no part of the claimed design.
